DRILL MOUNT

Alex Park, Burke, Idaho

Application September 11, 1936, Serial No. 100,377

1 Claim. (Cl. 255—53)

This invention appertains to new and useful improvements in power drills and more particularly to drills of the drifting type.

The principal object of the present invention is to provide a drill mount whereby the drill can be adjusted horizontally and vertically with ease as well as swung in a horizontal arc to meet various requirements.

Another important object of the invention is to provide a drill mount which will positively retain the drill sturdily without likelihood of self displacement.

Still another important object of the invention is to make various quick adjustments of the drill proper without any manual exertion or delay of time.

These and various other important objects and advantages of the invention will become apparent to the reader of the following specification.

In the drawings:—

Figure 1 represents a fragmentary side elevational view showing the drill in its mount.

Figure 2 is an enlarged fragmentary vertical sectional view.

Figure 3 is a fragmentary side elevational view of the drill mount.

Figure 4 is a fragmentary side elevational view of the horizontal supporting bar.

Figure 5 represents a fragmentary side elevational view of the vertical supporting post.

Figure 6 is a plan view of the lever and notches shown in Figure 2.

Figure 7 is an enlarged sectional view on line 7—7 of Figure 2.

Figure 8 is a cross section on line 8—8 of Figure 4.

Referring to the drawings wherein like numerals designate like parts it can be seen that numeral 5 generally refers to the drill proper 40 with the tool 6 extending therefrom.

Numerical 7 represents the carriage for the drill 5, the drill 5 being slidable thereon and controlled by the screw shaft 8 equipped with the crank 9.

Numerical 10 denotes the usual vertical supporting post for the drill 5. The horizontal supporting bar is denoted by numeral 11, one end being constructed to form one half section of the jacket generally referred to as numeral 12. These sections are denoted by reference character a—b and are hingedly connected together as at 13. The jacket 12 is provided with the detent generally referred to by numeral 14 and while this detent is retracted to permit rotation of the jacket 12 on the post 10, the collar generally re-

ferred to by numeral 15 supports the jacket and bar 11.

As is clearly shown in Figure 5, the vertical post 10 is provided with groups of circumferential recesses 16 within each of which are the teeth 17. Each group consists of two of the recesses 16 one for the detent 14 of the jacket 12 and the other for the detent 18 on the collar 15.

The horizontal bar 11 has circumferential extending recesses or reduced portions 19 each of 10 which is provided with teeth 20 on the bottom thereof and these recesses 19 are equidistantly spaced along the rod 11.

The carriage 7 is provided with the depending headed stud 21, the head 22 of which is received 15 by the socket structure 23 on the collar 24 which circumscribes the bar 11. The lower portion of this collar 24 is provided with a recess 25 therein for receiving the slider 26. This slider 26 is provided with teeth thereon to mesh with the teeth 20 in the recesses 19 of the bar 11. This slider 26 has the rigid screw 27 depending therefrom through an opening in the bottom of the socket 25 and is received by the nut 28 operating within the confines of the bracket 29 on the bottom of 25 the collar 24, this nut 28 being provided with an outstanding handle 30 which when swung from one point to another will feed the screw 27 upwardly along with the slider 26 so as to engage the teeth of the supporting rod 11. A swingable 30 spring pressed detent 31 at the free end is engageable into recesses 32 in the bottom of the bracket 29.

A similar form of detent is shown for the stud head 22, wherein the stud head 22 is provided 35 with circumferentially arranged teeth 33 with which the toothed plate 34 is engageable, said plate being provided with a screw extension 35 fed by the nut 36 which has a handle 37 and the retaining pawl 38. Obviously the collar 24 supporting the carriage 7 can be slid to any point desired on the rod 11 and retained in that position and obviously by operating the nut 26, the carriage can be freed so that it can be swiveled on a given plane.

The detents 14 and 18 are constructed in substantially the same way as the detents described in detail in Figure 3 as generally referred to by numeral 40.

While the foregoing specification sets forth the 50 invention in specific terms, it is to be understood that numerous changes in the shape, size and materials may be resorted to without departing from the spirit and scope of the invention as claimed hereinafter.

Having thus described the invention what is claimed as new is:—

In combination, an upright, a slidable jacket on the upright, a horizontal arm projecting from the jacket, a drill, a carriage for the drill, a collar on the arm, detent means between the jacket and the upright and between the collar and the arm, a swivelled connection between the carriage

and the collar, said detent means consisting in the provision of circumferential reductions on the upright and arm, teeth on the bottoms of the said reducements, and toothed followers on the jacket and collar feedable into the said reducements to engage the teeth therein. 5

ALEX PARK.
